US0D1089253S

(12) **United States Design Patent** (10) **Patent No.:** **US D1,089,253 S**
Evans (45) **Date of Patent:** **** Aug. 19, 2025**

(54) **DISPLAY SCREEN WITH GRAPHICAL USER INTERFACE**

(71) Applicant: **ICON VEHICLE DYNAMICS LLC**,
Riverside, CA (US)

(72) Inventor: **Dylan Samuel Evans**, Corona, CA
(US)

(73) Assignee: **ICON VEHICLE DYNAMICS LLC**,
Riverside, CA (US)

(**) Term: **15 Years**

(21) Appl. No.: **29/920,473**

(22) Filed: **Dec. 11, 2023**

Related U.S. Application Data

(62) Division of application No. 29/802,195, filed on Aug. 3, 2021, now Pat. No. Des. 1,012,944.

(51) **LOC (15) Cl.** **14-04**

(57) **CLAIM**

The ornamental design for a display screen with graphical user interface as shown and described.

DESCRIPTION

The sole FIGURE is a front view of a display screen with graphical user interface embodying the new design.

The outermost broken lines depict the display screen with graphical user interface in which the design is embodied that form no part of the claimed design. The remaining broken lines illustrate portions of the graphical user interface that form no part of the claimed design.

1 Claim, 1 Drawing Sheet
